UNITED STATES PATENT OFFICE.

PHILLIPS THOMAS, OF EDGEWOOD, PENNSYLVANIA, ASSIGNOR TO WESTINGHOUSE ELECTRIC & MANUFACTURING COMPANY, A CORPORATION OF PENNSYLVANIA.

GLOW-DISCHARGE MICROPHONE.

Application filed January 25, 1924. Serial No. 688,379.

My invention relates to telephone systems and apparatus and it has particular relation to sound wave translating devices.

Broadly speaking, the object of my invention is to provide an improved translating device for converting vibratory motion in a fluid medium into vibratory electric currents.

More specifically, an object of my invention is to provide a telephonic transmitter device whereby sound waves are more easily translated into correspondingly modulated electrical energy.

Another object of my invention is to provide a telephonic translating device which shall be characterized by its simplicity of design and operation, and which lends itself to inexpensive production.

Another object of my invention is to provide a telephonic translating device which shall be of greater sensitivity than prior devices.

Another object of my invention is to provide a telephonic translating device of the glow-discharge type wherein the intensity of response to pressure variations is substantially independent of the frequency of such variation.

A further object of my invention is to produce a glow discharge transmitter which is characterized by the use of only two electrodes and by the use of a secondary chamber surrounding a portion of the glow discharge.

As disclosed in my copending application Serial No. 600,822, filed November 14, 1922, glow discharge transmitter, a glow discharge maintained between electrodes manifests a variety of characteristics by which various portions can be recognized. These portions comprise a positive or anode column in contact with the positive electrode, and, following in sequence toward the negative electrode, a Faraday dark space, a negative light, a cathode dark space and a cathode glow, which latter is in contact with the negative electrode. I have found that the voltage current characteristic of this glow discharge varies with the pressure of the surrounding fluid medium.

In the practice of my invention, I provide a pair of mounted electrodes, a chamber surrounding the positive electrode, a source of steady direct current and a means for amplifying the vibratory currents produced by the change in current voltage character-

istic of the glow discharge with change in pressure.

I have found that the whole of the glow discharge is sensitive to sound variations. I have further found that this sensitivity may be greatly increased by surrounding the positive electrode with a chamber. This chamber is also made to enclose the positive column of the glow discharge and a small opening is provided for the passage of the current between the electrodes. This construction produces a glow discharge transmitter of high sensitivity and one of uniform sensitivity to all vibration frequencies. The sensitivity of the glow discharge transmitter constructed according to my invention is greater than that of the ordinary carbon grain microphone and it gives far more uniform response to various frequencies.

The gain in sensitivity produced by my invention over other constructions enables me to obtain a sufficiently large telephonic frequency current, for such applications as the modulation of the radio frequency output of a radio-sending apparatus, through the agency of a lesser number of stages of amplification than has heretofore been required.

Other objects and applications of my invention, as well as structural details, will be apparent from the following description when read in connection with the accompanying drawing, wherein:

Fig. 1 is a diagrammatic view of a preferred form of my invention incorporated into a sound-translating system,

Fig. 2 is a sectional view of the glow-discharge transmitter capsule, taken along a line corresponding to the line II-II in Fig. 1.

In the drawing is shown a glow discharge transmitter capsule 1, a source of high voltage direct current 2 and an amplifier 3. The glow discharge transmitter capsule 1 comprises a cylindrical supporting portion 4 having open ends, a positive electrode 5 mounted in a screw 6, a negative electrode 7 also mounted in a screw 8 and a cup piece 9, preferably of a non-conducting material and forming a chamber surrounding the positive electrode 5. The cup is of such size that all of its dimensions are less than the length of the highest frequency sound wave to which it is intended to be responsive, and that its dimensions are substantially

greater than the average excursion of an air particle in the sounds of the mean magnitude to which it is to respond. The opening of cup 9 is closed by a top plate 11, 5 which may be of conducting material, containing a hole 12 for the passage of the current of the glow discharge.

Conductors 13 and 14 conduct current from mains 15 and 16 which, in turn, are 10 connected to the current source 2.

The amplifier 3 may be coupled to the transmitter 1 by resistance, impedance, or transformer means. In Fig. 1 is shown a resistive coupling means and amplifier assembly 15 which comprises a triode thermionic discharge device 21, a grid leak 22, a grid stopping condenser 23, an output transformer 24, a plate current source 25, a filament current source 26 and a filament 20 control rheostat 27. The negative terminal 7 of the glow discharge transmitter 1 is connected through a condenser 23 to the grid of a triode 21. The positive terminal 5 of the glow discharge transmitter 1 is connected 25 by a lead 32 to the filament of the triode 21.

A grid leak 22 is shunted between the filament and the grid. The plate current source 25 and a transformer 24 are connected in series between the filament and the plate 30 of triode 21 and the secondary of transformer 24 serves as an output means for the amplified current.

In the operation of my improved transmitter, the sound waves to be translated into 35 electrical variations enter either one or both of the open ends of the cylindrical supporting portion 4. The sound waves, which, as is well known, comprise alternate zones of compression and rarefaction of the air, alter 40 the voltage-current characteristics of the glow discharge.

It has not been possible as yet to determine the precise mode of operation of this 45 modification of the glow discharge transmitter. From the information at present available, it is believed that the increase in sensitivity obtained by the addition of cup 9 and cover 11 is due to an air blast effect in and out through hole 12 in the cover 11 50 caused by pressure changes in the surrounding atmosphere.

It is probable that this air blast affects the positive column to accentuate the voltage current characteristics. It is, however, 55 found that the addition of this chamber, even though it is of relatively small volume, produces a very marked increase in the sensitivity and response of the glow discharge to the vibratory influence of sound waves. 60 Otherwise, the action of the transmitter is, in general, similar to that described in my copending application previously mentioned.

In order to insure that the discharge will 65 be a glow discharge and will continue to be a glow discharge, and not change into an arc,

I find that the source of potential must be high and that a current limiting device must be used. In addition to the specific dimensions already stated herein, the following actual constructions are noted. In one 70 specific embodiment of my invention, I employed a source of somewhat more than 4000 volts with a resistance in series between it and the discharge device of approximately one megohm. In another specific embodiment 75 of this invention, I employed a source of 4200 volts, together with a current limiting device which restricted the current to one millimeter. The current limiting device used in this instance was a saturation tube. 80

A characteristic difference between the glow discharge and the arc is found in the relation of current to voltage. In the arc the current is much greater and the voltage much smaller than in the glow discharge. 85 Another characteristic difference is that with the glow discharge the electrodes are relatively cool, never becoming incandescent, while with an arc the electrodes are hot and the cathode is usually more incandescent than any portion of the arc itself. 90

Irrespective of the exact theory upon which my invention operates, it is noted that variations in the voltage-current characteristics of the discharge may be amplified by 95 connecting a suitable amplifying device across the terminals thereof. In the specific form illustrated, the voltage variations across the discharge cause corresponding changes across the resistor 22, which changes 100 in turn cause the potential of the grid of the thermionic device to vary. The stopping condenser 23 serves to prevent the high potential from the source 2 from being applied to the grid of the triode 21. 105

In view of the foregoing, my invention provides means for producing a marked increase in the sensitivity and response of a glow discharge transmitter as compared to one made according to previous systems of 110 construction.

While I have shown only one embodiment of my invention in the accompanying drawings, it is capable of various changes and modifications without departing from 115 the spirit and scope thereof, and it is desired, therefore, that only such limitations shall be imposed thereon as are indicated in the prior art or in the appended claims.

I claim as my invention:

1. In combination, a pair of spaced electrodes, respectively positive and negative exposed to atmospheric pressure, means for establishing a glow discharge therebetween, and means for enclosing said positive electrode. 120

2. A translating device comprising a pair of spaced electrodes exposed to atmospheric pressure, means for establishing a glow discharge therebetween including a positive col- 125

umn, and a member surrounding said positive column.

3. A translating device comprising a pair of spaced electrodes exposed to atmospheric pressure, means for establishing a glow discharge therebetween including a positive column, and a member surrounding said positive column, said member having a single opening therein.

10 4. In an electrical system, the combination with a pair of electrodes exposed to atmospheric pressure and constituting the positive and negative terminals of a discharge device, of means for establishing a glow discharge therebetween including a positive column and having a voltage-current characteristic which varies with change in pressure, and means comprising a member surrounding said positive column for increasing said variation of said change in voltage-current characteristic with change in pressure.

5. A glow discharge sound-responsive device comprising a pair of electrodes exposed to atmospheric pressure, a supporting means therefor, and means for enclosing one of said electrodes.

6. A glow discharge sound-responsive device comprising a positive electrode and a negative electrode, supporting means for positioning said respective electrodes, means for enclosing said positive electrode, and means for establishing a glow discharge between said electrodes.

35 7. A glow discharge sound-responsive device comprising a positive electrode and a negative electrode, supporting means for positioning said respective electrodes, means for enclosing said positive electrode, and means for establishing a glow discharge between said electrodes, said means comprising a source of direct current having positive and negative terminals connected respectively to said electrodes.

45 8. A sound translating system comprising a sound-responsive apparatus and an amplifying device, said sound-responsive apparatus comprising a glow discharge transmitter having a positive electrode and a negative electrode, supporting means for positioning said respective electrodes, a member surrounding said positive electrode and means for establishing a glow discharge between said electrodes.

55 9. A sound translating system comprising a sound-responsive apparatus and an amplifying device, said sound-responsive apparatus comprising a glow discharge transmitter having a positive electrode and a negative electrode, supporting means for positioning said respective electrodes, a member surrounding said positive electrode, means for establishing a glow discharge be-

tween said electrodes, said amplifying means comprising a thermionic discharge device 65 having a cathode, an anode and a control electrode, a high resistance conductor connecting said control electrode to said cathode, said cathode being also connected to an electrode of said transmitter, said control electrode being capacitively connected to said other electrode of said transmitter and an output means, and a source of current respectively connected between said cathode and said anode. 70 75

10. In a glow discharge sound-responsive device comprising a positive and a negative electrode, a sound accentuating chamber surrounding said positive electrode.

11. In a glow discharge sound-responsive 80 device comprising a positive and a negative electrode, and means for producing a glow discharge therebetween, a chamber surrounding said positive electrode, the dimensions of said chamber being less than the length 85 of the shortest sound wave to which it is intended to respond, and greater than the average excursion of a particle of air produced by successive sound waves.

12. In a glow discharge sound-responsive 90 device comprising a positive electrode, a negative electrode, and means for producing a glow discharge therebetween having a positive column, and means for intensifying the response of said positive column to 95 sound, said means comprising a chamber surrounding said positive column and said positive electrode.

13. A glow discharge sound-responsive 100 device comprising a positive electrode and a negative electrode, means for producing a glow discharge therebetween, comprising a source of high voltage direct current, supporting means of insulating material for said electrodes for so spacing them as to 105 cause the passage of said glow discharge, a chamber surrounding said positive electrode, said chamber comprising a non-conducting cup having a bottom that is drilled and tapped for the passage of said positive electrode, and a metallic cover closing the top opening of said cup, said cover being drilled for the passage of said glow discharge. 110

14. A translating device comprising a pair of spaced electrodes, means for establishing a glow discharge therebetween, including a positive column, and a chamber surrounding said positive column, said chamber having a single opening thereto that is adapted and positioned for the passage of the glow discharge therethrough. 115

In testimony whereof, I have hereunto subscribed my name this 17th day of January, 1924.

PHILLIPS THOMAS.
